(57) **CLAIM**

The ornamental design of a gear motor casing, as shown and described.

DESCRIPTION

FIG. 1 is a front, top, right side perspective view of the gear motor casing, showing our new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The features shown in broken lines depict environmental structure only and form no part of the claimed design.

1 Claim, 7 Drawing Sheets(56)
